JAMES A. LEVI, OF NEW YORK, N. Y., AND OTTO PLOETNER, OF NORTH BERGEN, NEW JERSEY, ASSIGNEES TO ELESKO LACE AND EMBROIDERY CO., INC., A CORPORATION OF NEW JERSEY.

EMBROIDERY MACHINE.

Application filed March 30, 1922. Serial No. 547,984.

To all whom it may concern:

Be it known that we, JAMES A. LEVI and OTTO PLOETNER, citizens of the United States, the former a resident of the city, 5 county, and State of New York, and the latter a resident of North Bergen, in the county of Hudson and State of New Jersey, have invented certain new and useful Improvements in Embroidery Machines, of 10 which the following is a specification.

Our invention relates to embroidery machines and particularly to an attachment therefor whereby the pattern is formed by sewing on to a fabric such material as cord, 15 braid, chenille, threaded beads, or other materials for producing ornamentation on the fabric. In such machines provided with an attachment embodying our invention the ornamenting material does not pass through 20 the needles but is sewed to the fabric by the thread carried in the needles.

An object of our invention is to provide a machine of the class described with guiding means for the material that is to be 25 sewed upon the fabric.

Another object is to provide means for controlling the means which guides the material to be sewed on to the fabric in such a way as to maintain the guiding means in 30 position ahead of the needle along the line of the design, a further object being to prevent interference between the guiding means and stitching mechanism and to preserve synchronism in the operations thereof.

Another object of our invention is to provide means for controlling the means which guides the material to be sewed upon the fabric in such a way that the material will 35 positively and automatically be drawn alternately to opposite sides of the line of the design in synchronism with the stitching mechanism. The attainment of this object is of particular importance when the material which is sewed on to the fabric is of 40 such a nature that the needles cannot or preferably should not pass through the material as in the case of a cord or threaded beads, or threads comprising metallic fibers.

Another object of our invention is to provide 45 mechanism for maintaining the proper tension in the material to be sewed onto the fabric and comprising slack adjusting means for the material to be sewed on to the fabric which will withdraw any slack in the material to be sewed on when the guiding

means therefor is moved in such a direction as to tend to produce any slack in the material, and which will feed the material when the guiding means is moved in a direction which would tend to produce extra tension 60 therein.

Other and further objects and advantages of our invention will appear from the following specification taken in connection with the accompanying drawings forming a part 65 thereof and in which:

Fig. 1 is an end view of an embroidery machine, embodying our invention, parts of said embroidery machine, which are not modified by our invention being broken 70 away or generally indicated.

Fig. 2 is a top view of the construction shown in Fig. 1.

Fig. 3 is a detailed view on the line 3—3 of Fig. 2. 75

Fig. 4 is a detailed view.

Fig. 5 is a cross section on the line 5—5 of Fig. 4.

Fig. 6 is a cross section on the line 6—6 of Fig. 5. 80

Fig. 7 is a partial detailed view, and

Fig. 8 is a sectional view on the line 8—8 of Fig. 7.

Our invention is adaptable to well-known types of embroidery machines and it is therefore, unnecessary to illustrate and describe the complete mechanism of such a machine. However, parts of such a machine have been indicated in the drawings, in order to illustrate the adaptation thereto of one embodiment of our invention which we have illustrated for the purpose of disclosing our invention. In Fig. 1, the frame 1 which may be operated by a pantograph or any well-known automatic embroidery frame controlling-mechanism, carries the fabric 2, one of the fabric carrying rollers 3 being shown. The usual shuttle operating mechanism 5 mounted on the machine frame, parts 1^a of which are shown, operates the shuttle 6 in a well-known manner. The needle bar 7 carries a plurality of needles 8 and is operated in a well-known manner by means of the operating bars 9. These bars 9 are operated in a well known manner as stated from the main shaft 10. Each needle 8 is supplied with thread 11 which passes over the usual tension rods 12 which pass as is well-known from one end of the machine to the other. Associated with each needle is a material 110

guiding member 13. These guiding members are mounted upon a bar 14. In order to accomplish the objects of our invention we have provided means for so moving the 5 bar 14 that each guide 13 may be so moved that it is always ahead of the needle along the line of the design and also that it may if desired be alternately moved to opposite sides of the line of the design in synchronism 10 with the operation of the needle. Just as there are several needle bar operating devices distributed at points along the length of the machine, it may be desirable to have several devices distributed along the length 15 of the machine in the same manner for moving the guide supporting rod 14, but in order to simplify our description only one of these will be described. The shafts 15, 16, 17, 18, and 19 may all or only some of them run the 20 entire length of the machine, if several devices are used for moving bar 14. Shafts 15, 16, 17, and 18 are in any event operated from the main drive shaft 10 as hereinafter more fully described. Supported upon the 25 shafts 16, 17, and 19 is a frame member 20 as well shown in Figs. 4 and 5. This frame member is provided with ears 21 at its upper and lower portions which carry rods 22. A sub-frame member 23 (see Fig. 5) is provided with ears 24 at its upper and lower portions through which the rods 22 pass so that the sub-frame member may slide up and down upon the rods 22. The sub-frame member carries bracket arms 25 to which 30 are attached plates 26 (see Fig. 6) which support the rods 27 which may run from one end of the machine to the other and which pass through openings in the blocks 28 which carry the guide supporting bar 14. Extending out from each sub-frame 35 23 are ears 29 to which an eccentric strap 30 is pivoted by the pin 31. Within the eccentric strap 30 runs an eccentric 32 splined to the shaft 17. It will thus be seen that a rotation 40 of the shaft 17 will by reason of the operation of the eccentric 32 in the strap 30 cause the sub-frame 23 to slide up and down upon the rods 22 of the main frame 20 and cause the arms 25 to move up and down 45 carrying the rods 27 up and down imparting an up and down motion to the guide carrying bar 14. In one face of each block 28 there is a slot 35 in which fits a block 36 having an opening into which fits a stud 37. The stud 37 is carried by a rocker arm 38 pivoted at 39 in the face of the frame 20 and carrying at its lower end a stud 40 which fits into a cam slot 41 in the cam 42 which is splined upon the shaft 16. It will thus be 50 seen that a rotation of the shaft 16 will cause the cam slot 41 to act upon the stud 40 to rock the arm 38 about its pivot 39 so that the stud 37 will cause the block 28 to slide back and forth upon the rods 27 and the 55 guide carrying bar 14 being mounted upon

the block 28 will be moved back and forth imparting horizontal motion to the guides 13. Each of the frames 20 carries a dependent portion 43 into which fits a screw threaded member 44 fixed by the set screw 70 45 to the shaft 19. A rotation of the shaft 19 by means of the lever 46 will impart a sidewise motion to the frame 20 which is a more or less fixed adjustment as compared with the reciprocatory movements imparted 75 by a rotation of either of the shafts 17 or 16. The cam 42 being fixed between the arms 47 of the frame 20 by its bosses 42' and splined to the shaft 16 and the eccentric 32 being fixed between the arms 48 of the frame 80 20 by its bosses 32' and splined to the shaft 17 they will be moved along with the frame 20 when the threaded member 44 is rotated.

Referring to Fig. 6 A indicates the points where the needles reciprocate. If a guide 13 is at the position I rotation of the shaft 17 will cause the guide to reciprocate between positions I and II, or rotation of the shaft 16 will cause the guide 13 to reciprocate between the positions I and IV. If the guide 90 is in the position II rotation of the shaft 16 will cause it to reciprocate between the positions II and III. If the shaft 19 has been rotated to bring the guide 13 to the position V rotation of the shaft 17 will cause the 95 guide 13 to reciprocate between the positions V and VI.

The material 58 to be sewed onto the fabric is fed from spools 50 supported on the shaft 51 carried on the main frame by the 100 brackets 52. The material passes around a tension roller 53 and over a guide bar 54 carried by the bracket 55 from the needle carrying bar 7 and then through the guides 13. The tension roller 53 is freely supported on 105 a shaft 53' and a collar 56 adjustably fastened to the shaft 53' by set-screw 56' carries a spring tension spider 57 which presses against the end of the tension roller 53 to produce the necessary tension in the material 110 58. If the guide 13 is reciprocated between the points I and II or V and VI there will be slack in the material 58 each time the guide rises and a pull on the material against the tension therein each time the guide goes 115 down. In order to remove this slack or feed the material to insure that the guide will positively draw the material along the proper line during the stitching, we have provided slack adjusting means as follows: a ratchet 120 wheel 60' is fixed to shaft 53' and an arm 60 swinging on the shaft 53' has pivoted to it a double acting pawl 61 and a rod 62 which leads down to a crank or eccentric pin 63 carried by the shaft 18 which is driven 125 from the shaft 17 as hereinafter described. Carried on the main driving shaft 10 is a pulley 64 which may be connected to the shaft 10 by a one-position clutch 64'. A one-position clutch is used in order to pre- 130

serve proper synchronism between the stitching and guide moving mechanisms. The pulley 64 drives the belt 65 which in turn drives a pulley 66 on the shaft 15. The 5 shaft 15 carries a gear 67 which drives a gear 68 loosely mounted on the shaft 16 and a gear 69 loosely mounted on the shaft 17. A gear 70 keyed to the shaft 17 drives a gear 71 keyed to the shaft 18 to operate a slack 10 adjusting mechanism. A clutch member 72 splined upon the shaft 16 has in its face opposed to the gear 68 diametrically opposite notches 72' for cooperation with the diametrically opposite lugs 73 on the face of 15 the gear 68. In its opposite face it has a single notch 74 cooperating with a single lug 75 on the frame. Splined on the shaft 17 is a clutch member 76 which has in its face opposed to the gear 69 two diametrically opposite notches which cooperate with corresponding lugs 77 on the face of the gear 69. A clutch operating lever 78 is pivoted at 79 and carries a pin 80 cooperating 20 with a groove 81 in the clutch member 72 and a pin 82 cooperating with a groove 83 in the clutch member 76. The clutch member 76 also has diametrically opposite notches 84 cooperating with the lugs 85 on the frame. The lever 78 and clutch members 72 and 76 together with the notches 30 therein and the various lugs adapted to be accommodated by those notches constitute one embodiment of our invention wherein the method of our invention may be fully 35 carried out. But it is obvious that various modifications of the clutches whereby the shafts 16 and 17 are driven and of the means for operating those clutches may be made without departing from the spirit of our invention. Embroidery machines of the type 40 with which our invention is intended to be used are ordinarily controlled in a large part by automatic devices that among other things move the frame in order to produce 45 the desired design upon the fabric carried thereby and it is obvious that such devices well-known in this art for the control of various operations of embroidery machines of the type with which our invention is used 50 could be employed to effect such control of the guide moving mechanism of our invention that the same method of operation would be followed as is provided for by the specific mechanism that we have shown and 55 described, namely, the lever 78 and the clutches 72 and 76 that are operated thereby.

It will be observed that the gear 70 being keyed to the shaft 17, will only be rotated when the clutch 76 is in the position shown 60 in Fig. 2, that is to say, it will only be rotated when the shaft 17 is rotated to reciprocate the guides between the positions I and II, or V and VI. When the guides rise and fall a withdrawing and feeding of the 65 material 58 is necessary in order to pre-

vent undue slack or tension. Rotation of the gear 70 will impart rotation to the gear 71 and through the eccentric pin 63 reciprocation will be imparted to the link 62. Consequently a rising and falling of the arm 60 70 will occur. The first rotation of the shaft 17 will cause a lifting of the guides 13 and downward pull on the link 62 so that the pawl 61 will engage the ratchet wheel 69' and rotate it clockwise to withdraw the material 58. Further rotation of the shaft 17 and the eccentric 63 will cause the guides 13 to descend but will move the link 62 upwardly and the pawl 61 will impart a counter-clockwise motion to the ratchet wheel 80 60' and effect a feeding of the material 58 that is wrapped around the drum or tension roller 53. It will thus be apparent that in one phase of the operation of the machine and during the motion of the guides 13 along 85 a path crossing the line of the pattern or in order to keep them in advance of the needle, there will automatically be a feeding or withdrawing of the material 58.

The mechanism whereby the guides are 90 reciprocated laterally can be locked when the guides are in positions I or II by the stop lug 75 on the frame of the machine entering the recess 74 of the clutch member 72; and mechanical reciprocation between the positions I and II can only be effected when such locking exists. This follows since the clutch member 76, which is mechanically connected with the clutch member 72 through the lever 78 can only be sufficiently displaced on the 100 shaft 17 in the direction to establish a driving connection for this shaft, when the clutch member 72 has been displaced in the opposite direction to interrupt the driving connection for shaft 16 and the locking lug 105 75 has entered the recess 74 in the clutch member 72. One revolution of the shaft 16 is designed to effect one complete back and forth horizontal motion of the guides 13 and the lug 75 is fixed to the frame of the machine at such a point with relation to the clutch element 72, as will insure stopping of the guide bar 14 at the right hand limit of its horizontal travel by the lug 75 entering the recess 74 in the clutch element 72. This 110 leaves the guides in position I or II (Fig. 6) and the guides must be in this position before the clutch element 76 can be put into the position shown in Fig. 2, for driving shaft 17 to effect vertical reciprocation of 115 the guide members.

There can, therefore, in the normal or automatic operation of the machine, be no mechanical reciprocation between positions III and IV but by rotation of the shaft 19 the 125 guide can be carried while it is locked in position I over to position V and mechanical reciprocation between positions V and VI may be made as though the reciprocation were between positions I and II. The only 130

difference is that the shank of the guide 13 will lie on the opposite side of the line of reciprocation of the needle from that in which it lay during the reciprocation between positions I and II.

If the guide is in the position I and the clutch lever 78 is in the position shown in Fig. 2 and the clutch 64' is engaged, the shaft 17 will be rotated and cause the guide 10 to reciprocate between the points I and II and the slack adjusting mechanism will be operated from the gear 70. If the clutch lever 78 is swung to the right in Fig. 2 the shaft 16 will be driven and the guide 13 will 15 reciprocate between the positions I and IV if the clutch 76 has left the lugs 77 in one position, or between the positions II and III if the clutch 76 has left the lugs 77 in the other of its two positions, namely one half 20 a rotation removed from the first position. It will be apparent that the adjustment of the frame 20 by the threaded member 44 will not interfere with the operation of the guide moving mechanism operated from the 25 shafts 16 and 17. There is preferably only one lug 75 for cooperation with the clutch 72 as it is desired that when the shaft 16 stops rotating the cam 42 will be in such a position that the guide 13 is either at position I or II. There are two lugs 85 cooperating 30 with diametrically opposite notches 84 in the clutch member 76 so that when the shaft 17 stops rotating the guide 13 may be at either position I or II, so that it may reciprocate between positions I and IV or positions II and III when shaft 16 is rotated. Shaft 16 may be rotated by the collar 88 and the shaft 17 may be rotated by the collar 89 or gear 70 to secure minor 35 adjustments.

The pulley 64 is preferably half as large as the pulley 66 so that the guide will make one reciprocation for each complete forward and backward reciprocation of the needle 45 bar 7 driven from the shaft 10 in a well-known manner.

If it is desirable that the material to be sewed on to the fabric shall be a flat braid or tape we mount a disk 90 in an enlarged 50 loop '90' at the head of the guide 13 as shown in Fig. 7. The disk is provided with a slot 91 for a tape and it rotates freely so that the material may be properly applied to the fabric without becoming twisted.

The guide 13 is so formed that its shank 55 lies on the same side of the needle when it is in all of the positions I, II, III, and IV, but its shank is shifted to the opposite side of the needle when it is in either of the 60 positions V or VI. It will therefore be apparent from the above description that by providing only one lug 75 for holding the clutch member 72 in fixed position so that the cam 42 will always leave the guide 65 at position I or II the automatic guide

moving mechanism can never carry the guide across the line of reciprocation of the needle. It can only be carried across that line by manual operation of the shaft 19. It will furthermore be apparent that 70 if it is desirable to follow a design without moving the guide alternately to opposite sides thereof in synchronism with the stitch mechanism, the clutch lever 78 may be put in a neutral position and the shafts 16 75 and 17 may be rotated manually respectively by their collars 88 or 89 to bring the guide 13 to any point between the positions I and II or I and IV or II and III but not between the positions III and IV because the needle would be interfered with in that case. If it is desired to position the guide 13 directly at the left of the needle, it is brought to either position V or VI and then adjusted by rotation of the shaft 85 17. It will thus be apparent that the guide may be more or less permanently positioned at any point along the lines which it may be made to follow by the automatic mechanism.

While we have described one embodiment of our invention in great detail for the purpose of disclosing it, it is not intended that we shall be limited to the particular mechanism described; and it is especially 95 intended that different methods of driving the shafts may be employed as it is to be understood that we have merely shown one arrangement for securing proper synchronization of the motion of the material guides 100 13 with the stitching mechanism and whereby the guide is prevented from being reciprocated across the line of reciprocation of the needle during the normal automatic operation of the machine. Reciprocation 105 of the guide across the line of the needle is not impossible as the needle is ordinarily withdrawn far enough to permit the guide to move across its point and the cams and eccentrics are designed to make the shifting motion rapid as the guide crosses the line of the needle. It will be apparent, however, that by the arrangement of clutches disclosed or an equivalent arrangement, the 110 automatic movement of the guides will 115 never carry them to a position where they will interfere with the operation of the needles.

As above stated the fabric upon which the material is to be sewed is carried by a 120 frame operated in any wellknown manner. The operation of such a frame includes the movement of the frame so that the needles will form the prescribed pattern. The frame may also be moved so that in cases where 125 cords and similar materials are being sewed upon the fabric the stitches will be made alternately on opposite sides of the exact line of the pattern and a slight distance from that line. The distance from the 130

exact line at which the stitch may be placed is limited by two considerations: the stitch must not be conspicuous and it must be close enough to the cord or other similar materials to hold it very close to the line of the pattern. The limitation of the distance from the line at which the stitch may be placed adds to the importance of our invention because the guides in shifting from one side of the line of the pattern to the other carry the material well out of the way of the needle so that the stitch may be very close to the line or in some cases exactly upon it and the stitching thread will nevertheless properly cross over the top of the material to hold it in place upon the fabric.

What we claim as new and desire to secure by Letters Patent is:

1. In an embroidery machine having stitching means including needles, guides for material to be sewed onto the fabric, means for positively reciprocating the said guides in synchronism with the stitching means in a plane parallel with the plane of the fabric, and selective controlling means for determining the path for reciprocation of the guides, which path for each guide is constantly along a line all points of which lie ahead of its respective needle in the direction of advance of the line of the design.

2. In an embroidery machine having stitching means including needles, guides for material to be sewed onto the fabric, means for positively reciprocating the said guides in synchronism with the stitching means in a plane parallel with the plane of the fabric across the line of the pattern, and selective controlling means for maintaining each guide ahead of its respective needle as the direction of the line of the pattern changes.

3. In an embroidery machine having stitching mechanism including needles, guides for material to be sewed onto the fabric, means whereby said guides are reciprocated in a path ahead of the needles along the line of the pattern being followed, and means for maintaining tension in the material substantially constant.

4. In an embroidery machine having stitching mechanism including needles, guides for material to be sewed onto the fabric, and means whereby each guide may be reciprocated along the sides of a rectangle substantially surrounding the point of reciprocation of its respective needle.

5. In an embroidery machine having stitching mechanism including needles, guides for material to be sewed onto the fabric, and means whereby each guide may be moved to positions along the sides of a rectangle embracing the point of reciprocation of its respective needle.

6. In an embroidery machine having

stitching mechanism including needles, guides for material to be sewed onto the fabric, and means whereby each guide may be reciprocated along straight lines together embracing substantially the point of reciprocation of its respective needle.

7. In an embroidery machine having stitching mechanism including needles, guides for material to be sewed onto the fabric, and means for reciprocating each guide selectively along one of a plurality of lines in a plane parallel with the fabric.

8. In an embroidery machine having stitching mechanism including needles, guides for material to be sewed onto the fabric, and means for reciprocating each guide selectively along one of a plurality of lines in a plane parallel with the fabric, said lines together substantially enclosing the point of reciprocation of its respective needle.

9. In an embroidery machine having stitching mechanism including needles, guides for material to be sewed onto the fabric, means for setting each guide at a plurality of positions, and means for positively reciprocating said guides along a plurality of lines from one of said positions and along a given line from the other of said positions.

10. In an embroidery machine having stitching mechanism including needles, guides for material to be sewed onto the fabric, and means for positively reciprocating each guide in a plane parallel to the fabric along lines at an angle to one another.

11. In an embroidery machine having stitching mechanism including needles, guides for material to be sewed onto the fabric, and means whereby each guide may be reciprocated along parallel lines on opposite sides of each needle.

12. In an embroidery machine having stitching mechanism including needles, guides for material to be sewed onto the fabric, means for reciprocating said guides along lines at an angle to one another and means operative to prevent reciprocation along one of said lines during reciprocation along another of said lines.

13. In an embroidery machine having stitching mechanism including needles, guides for material to be sewed onto the fabric, means for reciprocating said guides between two points and between each of said points and respectively two other points and means operative to prevent reciprocation between said two last named points.

14. In an embroidery machine having stitching mechanism including needles, guides for material to be sewed onto the fabric, means for reciprocating said guides between two points and between each of said points and respectively two other

points, means for preventing reciprocation between said two last mentioned points, and means for setting said guides for reciprocation between points other than said first 5 named points and adjacent said last named points.

15. In an embroidery machine having stitching mechanism including needles, guides for material to be sewed onto the 10 fabric and means for reciprocating said guides along lines at an angle to one another and comprising means for reciprocating said guides along one of said lines and including a clutch engagable at two positions to effect reciprocation of said guides 15 and at one position to lock said last-mentioned means against operation, and means for reciprocating said guides along the other of said lines including a clutch engagable 20 at two positions to effect reciprocation of said guides and at either of two positions to lock said last-mentioned means against operation.

16. In an embroidery machine having 25 stitching mechanism including needles, guides for material to be sewed onto the fabric, and means for reciprocating said guides in a plane parallel to the fabric along selective portions of lines respectively 30 substantially surrounding the points of reciprocation of the needles.

17. In an embroidery machine having stitching mechanism including needles, guides for material to be sewed onto the 35 fabric, means for moving said guides to positions ahead of the needles along the line of the pattern being followed, and means for feeding the material as said guides are moved away from the supply thereof.

40 18. In an embroidery machine having stitching mechanism including needles, guides for material to be sewed onto the fabric, means for moving said guides to positions ahead of the needles along the 45 line of the pattern being followed, and means for withdrawing the material as the guides are moved toward the supply thereof.

19. In an embroidery machine having 50 stitching mechanism including needles, guides for material to be sewed onto the fabric, means for moving said guides to positions ahead of the needles along the line of the pattern being followed, and means for feeding the material as said guides are 55 moved in one direction and for withdrawing the material as the guides are moved in another direction.

20. In an embroidery machine having 60 stitching mechanism including needles, guides for material to be sewed onto the fabric, means for moving said guides to positions ahead of the needles along the line of the pattern being followed, means for imparting tension to the material, and 65 means for feeding the material as said

guides are moved in one direction and for withdrawing the material as said guides are moved in another direction.

21. In an embroidery machine of the horizontal needle type having stitching mechanism including needles, a bar, guides mounted on the said bar for material to be sewed onto the fabric by the stitching means, and means positively operated in synchronism with the stitching mechanism for moving said bar to carry the guides in a plane parallel to the fabric alternately to points on opposite sides of the line of the design followed by their respective needles, said points being in advance of the needles and said means carrying each of said guides from one point to the other directly over a path all points of which are ahead of its respective needle along the line of the pattern being followed. 80 85

22. In an embroidery machine having stitching mechanism including needles, guides for material to be sewed onto the fabric, means for imparting translatory motion to said guides along straight lines parallel 90 to the fabric to carry them to points about their respective needles, and means for limiting the operation of said first named means to prevent accidental motion of said guides across the points of reciprocation of the 95 needles.

23. In an embroidery machine having stitching means including needles, guides for material to be sewed onto the fabric, means for positively reciprocating said 100 guides in synchronism with the stitching means across the line of the pattern, means for producing tension in the material and means for feeding and withdrawing the material during reciprocation of said guides 105 to maintain constant the tension therein.

24. In an embroidery machine having stitching means including needles, guides for material to be sewed onto the fabric, means for positively reciprocating said 110 guides in synchronism with the stitching means selectively along one of two pairs of intersecting parallel lines.

25. In an embroidery machine having stitching mechanism including needles, 115 guides for material to be sewed onto the fabric and means for moving each guide selectively along any one of four lines together substantially surrounding the line of reciprocation of its respective needle. 120 120

26. In an embroidery machine having stitching mechanism including needles, guides for material to be sewed onto the fabric, a member mounted for sliding in a given direction, and a guide-supporting bar 125 mounted on said member for sliding in a direction transverse to said given direction.

27. In an embroidery machine having stitching mechanism including needles, guides for material to be sewed onto the 130

- 5 fabric, a member mounted for sliding in a given direction, a guide-supporting bar mounted on said member for sliding in a direction transverse to said given direction, and means whereby said member and bar may be reciprocated in synchronism with said stitching mechanism.
- 10 28. In an embroidery machine having stitching mechanism including needles, guides for material to be sewed onto the fabric, a member mounted for sliding in a given direction, a guide-supporting bar mounted on said member for sliding in a direction transverse to said given direction, and means whereby said member and bar may be selectively reciprocated in synchronism with said stitching mechanism.
- 15 29. In an embroidery machine having stitching mechanism including needles, guides for material to be sewed onto the fabric, a member mounted for sliding in a given direction, a guide-supporting bar mounted on said member for sliding in a direction transverse to said given direction, an eccentric operatively connected to said member to reciprocate it, and a cam operatively connected with said bar to reciprocate it.
- 20 30. In an embroidery machine having stitching mechanism including needles, guides for material to be sewed onto the fabric, a member mounted for sliding in a given direction, a guide-supporting bar mounted on said member for sliding in a direction transverse to said given direction, an eccentric operatively connected to said member to reciprocate it, a cam operatively connected with said bar to reciprocate it, and means for selectively operating said 40 cam and eccentric.
- 25 31. In an embroidery machine having stitching mechanism including needles, guides for material to be sewed onto the fabric, means for reciprocating each of said guides in a given direction, means for locking said first-named means when each guide is on a given side of its respective needle, and means for reciprocating each of said guides in a transverse direction.
- 30 32. In an embroidery machine having stitching mechanism including needles, guides for material to be sewed onto the
- 55 fabric, means for reciprocating each of said guides in a given direction, means for locking said first-named means when each guide is on a given side of its respective needle, means for reciprocating each of said guides in a transverse direction, and means for carrying each guide, while said first-named reciprocating means is locked, to the opposite side of its respective needle.
- 60 33. In an embroidery machine having stitching mechanism including needles, guides for material to be sewed onto the fabric, a frame, a member mounted on said frame for sliding in a given direction, and a guide-supporting bar mounted on said member for sliding in a direction transverse to said given direction, said frame being adjustable to position each guide on opposite sides of its respective needle.
- 65 34. In an embroidery machine having stitching mechanism including needles, guides for material to be sewed onto the fabric, means for imparting translatory motion to said guides along straight lines parallel to the fabric to carry said guides to points about their respective needles.
- 70 35. In an embroidery machine of the horizontal needle type, having stitching means including needles, guides for material to be sewed onto the fabric, means for positively reciprocating said guides in synchronism with the stitching means in a plane parallel with the plane of the fabric, each guide traversing a path all parts of which lie ahead of its respective needle in the direction of advance along the line of design.
- 75 36. In an embroidery machine of the horizontal needle type having stitching means including needles, guides for material to be sewed onto the fabric, means for positively reciprocating said guides in synchronism with the stitching means in a plane parallel with the plane of the fabric across the line of the pattern, and along paths all points of which lie ahead of their respective needles in the direction of advance along the line of design.

In testimony whereof, we have signed our names to this specification.

JAMES A. LEVI.
OTTO PLOETNER.
